UNITED STATES PATENT OFFICE.

MARTIN LANDENBERGER, JR., OF PHILADELPHIA, PENNSYLVANIA.

DESIGN FOR A CAPE.

Specification forming part of Design No. 6,660, dated May 20, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

The figure in the accompanying drawing clearly represents my design for the cloak-like garment commonly known as a circular. It has the usual semicircular outline, is cut straight across at the top, and is recessed at *a* at the point where it passes around the wearer's neck.

The garment is composed of a striped fabric, the stripes *b* of which extend vertically from the top to the bottom of the same, thus producing a very pleasing effect; and the hood *B* is of the peculiar triangular shape shown, and is composed of the same fabric as the body of the garment, so cut that the stripes shall extend diagonally across the same. At

the lower end of the hood is a bow, *d*, with long pendent ends, and the said hood, as well as the whole semicircular outline of the garment, is bound with a fringe, *e*, of the character represented.

Irrespective of the colors employed, I claim—

1. The design for a vertically-striped circular garment having a diagonally-striped hood, substantially as shown and described.
2. The design for the whole garment, including the minor ornamentation, substantially as described, and as represented in and by the accompanying drawing.

In testimony whereof I have signed my name to this specification in the presence of two subscribing witnesses.

MARTIN LANDENBERGER, JR.
